UNITED STATES PATENT OFFICE.

OTTO SCHWARTZ, OF DETROIT, MICHIGAN.

RADIATOR SHIELD.

Application filed October 2, 1922. Serial No. 591,813.

To all whom it may concern:

Be it known that I, OTTO SCHWARTZ, a citizen of the United States, and residing at Detroit, in the county of Wayne and State 5 of Michigan, have invented a new and Improved Radiator Shield, of which the following is a specification.

This invention relates to means adapted to be placed back of and over steam and hot 10 water radiators which are used for heating the rooms of dwellings, stores, and other edifices, which means will protect the walls, draperies and decorations immediately above or adjoining such radiators from the dust 15 which normally rises with the heated currents of air from such radiator, and this invention consists in the novel details of construction illustrated in the accompanying drawing and particularly pointed out in 20 the claims.

In the drawing, Fig. 1 is a perspective view of a radiator equipped with my novel shield. Fig. 2 is an end elevation of the 25 radiator with the end of the shield broken away, to disclose the details of construction. Fig. 3 is a perspective view of the upper portion of the shield with the cover removed. Fig. 4 is a perspective view of the securing device for this radiator shield.

Similar reference characters refer to like 30 parts throughout the several views.

The radiator shown in the drawing is of ordinary construction and consists of a series of connected sections 1 and 2, the latter being formed with supporting legs 3. The 35 radiator shield consists of a back, two end brackets, a deflector, a dust trough, a cover and a pair of securing devices. The back of this shield consists of a sheet 4 having side flanges 5 which are of less height than 40 the sheet 4. Secured to the sheet 4 is a curved deflector 6 held in position by means of the double fold 13 in the sheet 4 between the layers of which the lower edge of this 45 deflector may be gripped. Secured to the upper end of the back are the side brackets 8 which preferably have inwardly turned top flanges 10. Screws 11 and 12 secure these brackets to the sheet 4 and side flanges 5 of the back.

The brackets 8 are formed with notches 14 at their front ends to receive the supporting lips 15 of a trough 16, preferably formed of an integral sheet of metal. The bottom 50 of the trough and the ends 17 are continuous

with the lips 15, as shown in Fig. 3. This trough 16 is adapted to be lifted out of the notches 14 in the side brackets and emptied. As it is of sheet metal it may easily be disinfected, or it may be filled with a disinfecting solution, or it may contain spongy material which has absorbed a disinfecting solution.

The top 19 has end flanges 20 and longitudinal flanges 21 which extend down over the upper edge of the back plate 4, over the side brackets 8 and down in front of the upper part of the trough 16, as indicated in Fig. 2. This top is preferably freely removable. Attached to the inner sides of the side brackets 8 are securing devices, each consisting of a plate 24 adapted to be secured to a side bracket by means of screws 25 which pass through the slot 26 in this plate 24. The arms 27 extend inwardly 75 from this plate 24 and their inner ends are connected by means of the cross bar 28. The arms 27 have depressed portions 29 which are adapted to fit in between adjacent sections of the radiator and are slotted to receive the U-bolt 30 which extends around the bosses 32 of adjacent radiator sections. When the nuts 33 are screwed down, these 80 U-bolts will secure the side brackets 8 firmly to the radiator and thus hold the 85 shield in position.

The heated air which rises between and back of the radiator sections is confined by the back plate 4 and passes out to some extent diagonally forward between the vertical portions of the sections. That portion of the heated air which strikes the deflector 6 also passes forward. The dust which impinges on the deflector 6 slides along the lower side of the top until it reaches the 90 front of the trough 16 where a cushion of heated air is produced, sufficient to check the forward movement of the air and cause a large portion of the dust to settle in the trough 16.

The deflector 6 extending below the top 19 prevents this top from becoming overheated. If desired, the deflector 6 (Fig. 3) may be made quite short to permit the heated air to flow along the lower surface of the top 100 19. This deflector, instead of being secured to the back sheet by the fold 13, may be secured to the back 4^a by means of screws 7.

The other details and proportions of this 105 radiator shield may also be changed by those 110

skilled in the art to adapt this shield to radiators of different heights, widths, and lengths, without departing from the spirit of my invention as set forth in the following claims.

I claim:

1. A radiator shield comprising a back plate, side brackets attached to the upper end of the back plate, a curved deflector attached to the upper end of the back plate and curving forwardly, a dust trough mounted at the front ends of the brackets, a cover extending over the top of the dust trough and side brackets, and means to se-

cure the shield to a radiator comprising inwardly extending members secured to the side brackets and U-bolts engaging portions of the radiator and passing through said brackets whereby the brackets may be rigidly secured to the radiator.

2. A radiator shield embodying a back, a top and side plates, and means to attach the shield to a radiator comprising inwardly extending members attached to the side plates and U-bolts engaging portions of the radiator and passing through said inwardly extending members.

OTTO SCHWARTZ.
